BITUMINOUS BURNER HEAD

Reuel Osmond Ladd, Elmira, N. Y.

Application July 13, 1945, Serial No. 604,741

18 Claims. (Cl. 110—45)

My invention relates to bituminous burner heads for heating units and the like, and the principal object thereof is to provide a head for efficiently and economically burning pulverized or inexpensive fine or waste bituminous coal of any grade or type, which coal is fed into the burner head by means of a screw flight or the like and discharged upwardly from the head in the form of a hollow cylindrical column between a central rotating draft intensifier cylinder and an outer rotating annular draft intensifier cap, the cap and cylinder rotating in opposite directions; means being provided in the cylinder and cap for admitting air through the cylinder and cap to the adjacent inner and outer portions of the cylindrical column of coal; means being provided for maintaining spacing between the faces of the column of coal and the cylinder and cap; and means being also provided for evenly distributing the coal fed upwardly around and between the cylinder and cap; my construction thereby providing draft intensifiers at the inner and outer walls of the column of coal so that the coal which is constantly forced upwardly between the cylinder and cap will be completely consumed at the upper end of the coal column, the ash dropping over the outer side of the cap; my invention thus making it possible to economically and efficiently burn pulverized or fine bituminous coal.

Another object of my invention is to provide a burner of the above type in which water is sprayed into the mass of coal at the bottom of the cylindrical column, to furnish the required amount of moisture to the coal particles so that when same reach the point of combustion and become heated, the vapor and steam generated thereby will unite with the carbon and gases released by combustion of the coal, and will produce a smokeless, gas-like flame of high heat intensity.

Other minor objects of the invention will be hereinafter set forth.

I will explain the invention with reference to the accompanying drawings, which illustrate one practical embodiment thereof to enable others familiar with the art to adopt and use the same; and will summarize in the claims the novel features of construction, and novel combinations of parts, for which protection is desired.

Figure 1 is an elevational view of my novel bituminous burner head.

Fig. 2 is a top plan view of the base of the burner head, detached.

Fig. 3 is a vertical section through the burner head on the line 3—3, Fig. 1.

Fig. 4 is a top plan view, partly in section, of the burner head.

Fig. 5 is a transverse section on the line 5—5, Fig. 4.

As shown, my bituminous burner head preferably comprises a base 1, of general circular shape, having an outer wall 1a contracting towards its lower closed end 1c, as shown more particularly in Figs. 3 and 5; and an inner wall 1b, said walls being separated or spaced apart at their upper ends.

One side of outer wall 1a has an opening 1d of substantially rectangular shape, as shown, adapted to communicate with a duct (not shown) leading from a blower which introduces air into the base between the walls 1a and 1b, for the purpose hereinafter described. Diametrically opposite the opening 1d is a coal inlet 1e of cylindrical shape through which extends a motor driven shaft 11. Opposite the end of shaft 11 is a bearing 10 (Fig. 3) in an upward extension of base 1c; and shaft 11 terminates in a yoke 11a fixed to a shaft 10a, journaled in bearing 10, said yoke 11a maintaining shaft 10a in the bearing 10 with the help of the gear 9 on its outer end, which gear 9 is retained thereon by means of a washer 11b and nut 11c, as shown in Fig. 3, to maintain shaft 10a from axial movement in said bearing 10. On shaft 11 is a spiral conveyor flight 10 for feeding coal from a hopper (not shown) into the base 1 in the direction of the arrow A (Fig. 3).

The inner end of feed duct 1e is open at its top and registers with an upwardly flaring wall 1f (Figs. 3 and 5) directing the mass of coal fed through duct 1e upwardly and outwardly, the upwardly inclined walls 1f connecting the outlet of duct 1e with the lower edge of inner wall 1b of base 1 throughout the major portion of its circumference. At the inner lower end of outer wall 1b is an annular shoulder 1g, for the purpose hereinafter described.

Seating upon and bridging the walls 1a, 1b of the base 1 is a rotatable annular cap member 6 whose walls are of inverted U-shaped cross section, the inner wall 6x overlying and contacting the inner face of inner wall 1b of base 1 with its lower end disposed slightly above the annular shoulder 1g as shown in Fig. 3, while the outer wall 6y of cap 6 has an enlarged bead at its lower end provided with an annular recess conforming with and receiving in slightly spaced relation the upper edge of outer wall 1a of base 1.

Within the cap 6 on the inner wall 6x thereof is an annular ring gear 7 having teeth extending from its lower face, ring gear 7 being disposed

slightly above the top of inner wall $1b$ of base 1 and serving as a means for rotating cap 6 . In order to assist in rotatably supporting cap 6 on base 1 , I provide idler gears or rollers 20 engaging the teeth or underside of ring gear 7 , as shown more particularly in Figs. 3 and 5, said gears being carried by stub shafts having enlarged beads journaled in T slots 21 (Fig. 3) extending downwardly in the upper end of the inner wall $1b$ of base 1 at spaced intervals, and preferably maintaining a slight clearance between the lower end of the walls of the cap and the upper ends of the walls $1a, 1b$ of the base.

Extending radially inwardly from the wall $1b$ of base 1 , and preferably forming an integral part thereof, is a horizontally disposed bracket $1m$ (Figs. 2 and 3) supporting a central casting $1h$ hereinafter described. In the upper portion of bracket $1m$ is journaled a shaft 4 above and parallel with a flight shaft 11 , said shaft carrying on its outer end a large gear 8 meshing with gear 9 on flight shaft 11 , said gear 8 also meshing with the teeth on the ring gear 7 , which is carried by the cap 6 , whereby rotation of the flight shaft 11 will rotate the cap 6 through the gears $9-8$ and annular ring gear 7 . Gear 8 is maintained on shaft 4 by means of a washer $8a$ and a nut 14 as shown in Figs. 1 and 3.

Preferably the idler rollers or gears 20 are spaced the same angular distance apart at each side of the shaft 4 of gear 8 , thus forming a three-point suspension for cap 6 . However, a greater number of idler rollers or gears 20 may be provided, as desired.

At the outer end of the bracket $1m$ is a casting $1h$ of hollow inverted cone shape, terminating substantially in the plane of the shoulder $1g$, and within the head $1h$ on shaft 4 is a beveled pinion 5 keyed thereto so as to rotate with said shaft. Seated upon the top of the casting $1h$ is a bearing spider 2 (Fig. 3) secured thereto in any desired manner in fixed position, said spider 2 having a vertical bore therein for a shaft 13 having at its upper end connected with a central rotatable intensifier cylinder 3 , shaft 13 carrying at its lower end a beveled pinion 12 meshing with the beveled pinion 5 , whereby the cylinder 3 will be rotated by and with the shaft 4 but in the opposite direction from the rotation of cap 6 , as indicated by the arrows in Fig. 4.

Cylinder 3 is hollow and closed at its upper end, while its lower end rotatably engages the outer periphery of bearing spider 2 and the top of the casting $1h$, the cylinder having an inner open spider $3a$ (Fig. 3) provided with a non-circular bore receiving the correspondingly shaped upper end of shaft 13 , as shown in Fig. 3, whereby rotation of shaft 13 will rotate cylinder 3 therewith.

By the above construction, forced air is free to circulate from the interior of casting $1h$ below shaft 4 up around the gears 5 and 12 , past the spiders 2 and $3a$ into the interior of cylinder 3 which as stated is closed at its upper end. An air duct $26a$ extends through the bracket $1m$ below the journals of shaft 4 and connects the lower end of the casting $1h$ with the space between walls $1a-1b$ of base 1 , as shown in Fig. 3. Similar ducts $26b$, shown in Figs. 2, 4 and 5, connect the interior of casting $1h$ with the space between the walls $1a-1b$ of the base, ducts $26b$ being preferably disposed below the idler rollers or gears 20 , as shown in Figs. 4 and 5, although they may be differently spaced, if desired. Thus the air forced into opening $1d$ of the base may circulate freely around

the space between walls $1a-1b$ of the base, through the ducts $26a-26b$ and into the casting $1h$, said air passing upwardly into the interior of hollow cylinder 3 .

On the exterior of the rotating cylinder 3 is a spiral rib 15 extending throughout the height thereof, and in the sides of the cylinder 3 between the convolutions of rib 15 are air discharge holes 23 permitting the air within the cylinder to pass therethrough into the adjacent surface of the cylindrical mass of coal adjacent said cylinder, a space being maintained between the mass of coal and the rotating cylinder 3 by the action of the spiral rib 15 . At the lower end of cylinder 3 are radial lugs $3x$ adapted when rotating with cylinder 3 to enter the mass of coal adjacent the base of the cylinder and assist in evenly distributing or spacing the coal as it is fed upwardly around the lower periphery of said cylinder.

On the inner wall $6x$ of the rotating cap 6 opposite the lugs $3x$ of cylinder 3 are corresponding radial lugs $6b$ for serving the same purpose of assisting in distributing and spacing the mass of coal fed upwardly through the feed duct $3e$ when positioned adjacent the inner wall $6x$ of the cap. In the inner wall $6x$ of cap 6 are a series of holes 25 above ring gear 7 permitting forced air within the under side of cap 6 to pass inwardly into contact with the adjacent surface of the cylindrical column of coal and between certain of the holes 25 are inwardly extending slanting ribs $6r$ which may be slanted in any direction (Fig. 3) preferably of arcuate form serving to maintain a slight spacing between the column of coal and the inner wall $6x$ of the rotating cap.

In order to obtain perfect combustion, water is introduced in the form of a controlled spray $18a$ (Fig. 3) located at the bottom of the casting $1h$ fed through a valved pipe 17 , whereby substantially each particle of coal may receive its required amount of moisture so when the coal particle reaches its point of combustion, and is heated, and the vapor and steam generated will unite with the carbon and gases released by the production of combustion, and a smokeless gas flame of high heat intensity is produced.

In operation

In operation, a blower (not shown) directs air into the opening $1d$ of base 1 , and coal is forced into the base by the screw flight 19 through feed duct $1e$, the coal being then forced upwardly between the centrally rotating intensifier cylinder 3 and the annular outside intensifier cap 6 , the cap and cylinder rotating in opposite directions. Some of the air forced into base 1 passes through the ducts $26a$ and $26b$ into the casting $1h$ and up past the gears 5 and 12 and the spiders 2 and $3a$ in the direction of the arrows in Figs. 3 and 5 into the interior of cylinder 3 from whence the same is discharged through holes 23 into the adjacent portions of the cylindrical column of coal emerging from the top of the burner head. During operation, the cylinder 3 is rotated from the conveyor shaft 11 through the gears $9-8$, shaft 4 and beveled gears 5 and 12 , and shaft 13 , while the cap 6 is rotated from shaft 11 , from the gears $9-8$ and the annular ring gear 7 , the members 6 and 3 rotating in opposite directions. The air under cap 6 also is discharged through holes 25 of the rotating cap 6 into the adjacent portions of the column of coal emerging from the top of the burner head.

The air emerging from the holes 23 of cylinder 3 and holes 25 of cap 6 enters the adjacent por-

tions of the column of coal, while the rotating ribs 15 and 6r create and maintain definite spacings between the vertical draft intensifier cylinder 3 and intensifier cap 6, thus maintaining a channel for the air emerging from holes 23 and 25 so that same may come in complete contact with the entire inner and outer surfaces of the coal column, the lugs 6p and 3x on the cap 6 and cylinder 3 extending into the coal column and distributing the coal evenly around the entire circumference of the column. The air from the ports 23 and 25 thus provides for complete combustion at the entire inner and outer surfaces of the coal column. As the coal is constantly forced upwardly by flight 19 between the cylinder 3 and cap 6, it assumes a cylindrical shape of a definite thickness and becomes completely consumed at the top of its travel, the ashes falling over the outer side of the cap 6.

I do not limit my invention to the exact form shown in the drawings, for obviously changes may be made therein within the scope of the claims.

I claim:

1. A powdered fuel burner comprising a base having spaced inner and outer walls open at the top; a feed duct therein terminating in an upwardly flaring conical wall connecting with the lower end of the inner wall; an annular cap having walls of inverted U-shaped cross-section rotatably mounted on the base and bridging the inner and outer walls of the base, the inner wall of the cap having a series of air discharge openings therein; a hollow substantially inverted conical central member in the base open at its upper end and disposed within the upwardly flaring conical wall of the base; a hollow cylinder having a closed upper end and open lower end rotatably journaled on said central member coaxially with the cap; said cylinder having openings therethrough; means for rotating the cap and cylinder; said base having an opening for receiving air under pressure introduced thereinto passing between the walls thereof; and means for passing air from the said space in the base into the central member, whereby the air will be discharged through the holes in the cap and cylinder into the adjacent faces of the column of fuel emerging from the top of the burner between the cap and cylinder.

2. In a burner as set forth in claim 1, said inner wall of the cap having inclined inwardly projecting ribs disposed between certain of said openings; and having radially disposed mixing lugs adjacent its lower end.

3. In a burner as set forth in claim 1, said cylinder having a spiral rib on its external wall; and having radially disposed mixing lugs adjacent its lower end.

4. In a burner as set forth in claim 1, a spray head at the lower end of the central member adapted to emit water into the fuel adjacent said opening; and a water duct leading to said spray head.

5. A powdered fuel burner comprising a base having spaced inner and outer walls open at the top; a duct in said base having a shaft therein carrying a spiral flight for feeding fuel inwardly of the base, said duct having an opening at its inner end terminating in an upwardly flaring conical wall connecting with the lower end of the inner wall; an annular cap having walls of inverted U-shaped cross-section rotatably mounted on the base and bridging the inner and outer wall of the base, the inner wall of the cap having a series of air discharge openings therein; a hollow

substantially inverted conical central member in the base open at its upper end and disposed within the upwardly flaring conical wall of the base; a hollow cylinder having a closed upper end and open lower end rotatably journaled on said central member coaxially with the cap; said cylinder having openings therethrough; means for rotating the cap and cylinder in opposite directions by said flight shaft; said base having an opening for receiving air under pressure introduced thereinto passing into the space between the walls thereof; and means for passing air from the said space in the base into the central member, whereby the air will be discharged through the holes in the cap and cylinder into the adjacent faces of the column of fuel emerging from the top of the burner between the cap and cylinder.

6. In a burner as set forth in claim 5, said inner wall of the cap having inclined inwardly projecting ribs disposed between certain of said openings; and having radially disposed mixing lugs adjacent its lower end.

7. In a burner as set forth in claim 5, said cylinder having a spiral rib on its external wall; and having radially disposed mixing lugs adjacent its lower end.

8. In a burner as set forth in claim 5, said rotating means comprising a second shaft disposed above and parallel with the flight shaft; a pinion on the first shaft; a gear on the second shaft meshing with said pinion; a third shaft disposed coaxially of the cylinder; intermeshing bevel gears within the central member on the second and third shafts; an annular ring gear carried by the cap and disposed above and meshing with the gear on the second shaft.

9. In a burner as set forth in claim 5, said rotating means comprising a second shaft bracket disposed above and parallel with the flight shaft; a pinion on the first shaft; a gear on the second shaft meshing with said pinion; a third shaft disposed coaxially of the cylinder; intermeshing bevel gears within the central member on the second and third shafts; an annular ring gear carried by the cap and disposed above the upper end of the inner wall of the base and meshing with the gear on the second shaft; and idler gears journaled in the inner wall of the base and meshing with the ring gear, said idler gears and the said gear on the second shaft supporting the cap by a three-point suspension.

10. In a burner as set forth in claim 5, said air admitting means comprising ducts connecting the space between the walls of the base and the interior of the said central member.

11. In a burner as set forth in claim 5, a spray head at the lower end of the central member adapted to emit water into the fuel adjacent said opening; and a valved water duct leading to said spray head.

12. A powdered fuel burner comprising a base having spaced inner and outer walls open at the top, a duct in said base having a shaft therein carrying a spiral flight for feeding fuel inwardly of the base, said duct having an upward opening in its inner end disposed substantially centrally of the base; an upwardly flaring conical wall in the base connecting the opening with the lower end of the inner wall; an annular cap having walls of inverted U-shaped cross-section rotatably mounted on the base and bridging the inner and outer walls thereof, the inner wall of the cap above the inner wall of the base having a series of air discharge openings therein; a hollow substantially inverted conical central member in the base supported by a bracket extending from the

inner wall thereof, said casting being disposed within the upwardly flaring conical wall of the base; a hollow cylinder having a closed upper end rotatably journaled on said central member coaxially with the cap; said cylinder having openings therethrough; means for rotating the cap and cylinder in opposite directions by said flight shaft; said base having an opening for receiving air under pressure into the space between the walls thereof; and means for passing air from the said space in the base into the central members, whereby the air will be discharged through the holes in the cap and cylinder into the adjacent faces of the column of fuel emerging from the top of the burner between the cap and cylinder.

13. In a burner as set forth in claim 12, said inner wall of the cap having inclined inwardly projecting ribs disposed between certain of said openings; and having radially disposed mixing lugs adjacent its lower end.

14. In a burner as set forth in claim 12, said cylinder having a spiral rib on its external wall; and having radially disposed mixing lugs adjacent its lower end.

15. In a burner as set forth in claim 12, said rotating means comprising a second shaft disposed above and parallel with the flight shaft; a pinion on the first shaft; a gear on the second shaft meshing with said pinion; a third shaft disposed coaxially of the cylinder; intermeshing bevel gears within the central member on the second and third shafts; an annular ring gear carried by the cap and disposed above and meshing with the gear on the second shaft.

16. In a burner as set forth in claim 12, said

bracket being disposed above and parallel with the spiral flight; a second shaft journaled in said bracket; and said rotating means comprising a pinion on the first shaft; a gear on the second shaft meshing with said pinion; said pinion and gear being disposed within the space between the inner and outer walls of the base; a third shaft disposed coaxially of the cylinder; intermeshing bevel gearing within the central member on the second and third shafts; an annular ring gear carried by the cap and disposed above the upper end of the inner wall of the base and meshing with the gear on the second shaft; and idler gears journaled in T-slots in the inner wall of the base and meshing with the ring gear, said idler gears and the gear on the second shaft supporting the cap and being evenly spaced apart around the inner wall of the base.

17. In a burner as set forth in claim 12, said air admitting means comprising a duct extending through said bracket connecting the space between the walls of the base and the interior of the said central member, the upper end of the casting being open and communicating directly with the open lower end of the cylinder; and other ducts connecting the space between the walls of the base with the casting, said other ducts and the said bracket being evenly spaced apart around the inner wall of the base.

18. In a burner as set forth in claim 12, a spray head at the lower end of the central member adapted to emit water into the fuel adjacent said opening; and a valved water duct leading to said spray head.

REUEL OSMOND LADD.
